United States Patent Office

Des. 224,404

Patented July 25, 1972

224,404

FAUCET

Dee L. Jenner, San Pedro, Calif., assignor to
Hi-Shear Corporation, Torrance, Calif.

Filed Oct. 5, 1970, Ser. No. 25,332

Term of patent 14 years

Int. Cl. D23—01

U.S. Cl. D23—25

FIG. 3

FIG. 2

FIG. 1

FIG. 4

FIG. 5

FIG. 1 is a perspective view of a faucet embodying my new design;

FIG. 2 is an elevational view taken from the left end thereof, the right end being a mirror image of the end shown;

FIG. 3 is another elevational view taken from the left end thereof showing the handle in a different position;

FIG. 4 is a front elevational view thereof; and

FIG. 5 is a rear view thereof.

I claim:

The ornamental design for a faucet, as shown and described.
